GOVERNOR

Harry P. Reiber, Williamsport, Pa., assignor of
forty per cent to Arthur H. White, New York,
N.Y.

Application February 24, 1941, Serial No. 380,233

2 Claims. (Cl. 170—163)

My invention relates to governors or regulators and more particularly to a centrifugally responsive governor mechanism for maintaining a predetermined relationship between the pitch of the blades of a variable pitch airplane propeller and the speed of rotation (R. P. M.) of the engine shaft driving the propeller.

One of the objects of my invention is to provide a simple governor mechanism of the type defined which can be coupled to the drive shaft of an airplane engine and which can be controlled manually from the cockpit.

Another object is to provide a centrifugally operated governor mechanism which is responsive to variations in the R. P. M. of an engine shaft to operate associated mechanism for varying the pitch of the propeller blades to such an extent and in the proper direction whereby the desired R. P. M. of the shaft can be substantially maintained automatically at a predetermined value.

Another object is the provision of means responsive to the action of centrifugal force to electrically control a mechanism for varying the pitch of the blades of an airplane propeller.

A further object resides in the provision of means responsive to the action of centrifugal force for electrically selecting mechanism for varying the pitch of the blades of a variable pitch propeller, in which variations in the degree of centrifugal forces applied to said means will correspondingly vary the flow of electrical current in the selector circuit.

Another object is to construct a governor of the above mentioned character which is extremely simple in design and construction, sensitive and efficient in operation and which can be produced at low cost.

A still further object of my invention is to provide simple means for preselecting the approximate R. P. M. of the shaft at which the governor will respond to effect a variation in the pitch of the propeller blades.

Other objects and advantages of my invention will become more apparent from the following description of one embodiment thereof, reference being made to the accompanying drawing in which like reference characters are employed to designate like parts throughout the same;

In the drawing:

Figure 1 is a longitudinal section of a governor assembly employing my invention;

Figure 2 is a vertical transverse section taken on line 2—2 of Figure 1;

Figure 3 is a section taken on line 3—3 of Figure 1;

Figure 4 is an end view taken in the direction of line 4—4 of Figure 2 and shows part of the assembly in cross section; and

Figure 5 is a wiring diagram illustrating the electric circuits for controlling overspeeding and underspeeding mechanism similar to that illustrated in a copending application, Serial Number 336,620, filed May 22, 1940 in which I am one of the joint applicants. This view also illustrates how the present invention may be connected electrically in these circuits for automatically controlling the operation of the blade pitch changing mechanism.

In carrying out my invention it should be pointed out that the same is particularly desirable for use in connection with variable pitch propellers as a means of automatically varying the pitch of the blades in a definite relationship to the R. P. M. of the engine shaft. Therefore brief reference is made to the above identified copending application of myself and Jack B. Reiber in which is disclosed mechanical means for effecting a pitch variation through suitable gearing and the timely operation of magnetic clutches by the pilot.

In operating an airplane a great demand is made upon the faculties of the pilot by the necessity of constant observance of numerous instruments indicating the performance of the various parts of the machine as well as the conditions of flight.

One of the duties which require the attention of the pilot of a plane having a variable pitch propeller is that he must from time to time adjust the pitch of the blades in relation to the R. P. M. of the engine shaft to maintain efficient operation of the plane and engine. This is particularly true in steep climbing or in diving.

The present invention is concerned chiefly with the provision of means whereby this relationship between shaft R. P. M. and blade pitch can be maintained automatically without especial attention of the pilot as will more fully appear hereinafter. Furthermore, by the present invention this relationship may be varied at the will of the pilot as he sees fit by manual adjustment of the governor.

Referring more specifically to the accompanying drawing which illustrates one embodiment of my invention, the governor casing comprises the housing members 1 and 2 which may be secured together by means of the screws 3.

The housing member 1 comprises a tubular portion extending substantially axially of the general assembly and a cover plate 4, the latter fitting snugly against the open end of the housing member 2.

Within the housing 2 a rotor 5, driven by the drive shaft 6, is journaled in suitable thrust bearings 7, the drive shaft 6 projecting outwardly of the casing as shown and having suitable driving connection with an engine or driver shaft (not shown).

The rotor 5 carries a plurality of metal tubes 8 and 9 arranged in chordal relation to the circumference of the casing and welded or otherwise secured to the rotor 5. Telescoped within each of the tubes is a tube 10 of electric insulating material, the ends of the tubes 10 extending a short distance beyond the ends of the metallic tubes 8 and 9 as a protection against short circuits around the carbon piles as will be seen later in this description.

Each of the insulating tubes 10 houses a carbon pile 11, that is, a plurality of discs of carbonaceous material each having good electrical conduction characteristics, said discs being arranged in a pile or in face to face relation as shown.

As is well known, when the pile is put under axial compression, the electrical resistance through the pile decreases in proportion to the pressure applied, and as the discs of the pile tend to separate one from the other, the electrical resistance through the pile increases.

The device is connected with a source of electrical energy as indicated in Figure 5. In Figure 1 a binding post 12, insulated at 13 from the casing 2, is connected with an annular conductor 14 retained in an insulating band 15 carried by the casing 2.

When two carbon piles are employed, as shown in the drawing, I provide a pair of current collection rollers 16 mounted in suitable holders 17 operating against the compression of light springs 18 within recesses formed in the bases 19 to normally thrust the rollers outwardly so that they will always be urged into good electrical contact with the annular conductor 14. In order to maintain the rollers in proper alignment with the conductor 14, the stems 20 are slotted at 21 to receive guide pins 22 carried in the holders 17. Each of the roller mounts or bases 19 is carried by the rotor 5 but insulated from it at 23, there being conductors 24 and 25 leading from the bases 19 respectively to the yoke support 26 which is also insulated at 27 from the rotor 5 (see Figure 4).

In further carrying out my invention, I have provided means whereby a predetermined initial force of compression may be applied to the discs of the respective carbon piles 11. At each end of each of the piles 11, there are provided a pair of spaced follower plates or discs of metal 28 and 29 respectively having therebetween a coiled compression spring 30.

I will now describe in detail the mechanism shown in the embodiment illustrated in the drawing for exerting forces to vary the compression of the springs 30 or to relieve said forces.

In the outer end of the axially extending casing member 1, I have provided a bearing support 31 for slidably supporting the rack 32. A shaft 33 extends transversely within the casing 1 and carries a keyed pinion 34 having its teeth in mesh with the rack 32 within the casing. The outer end of the shaft carries a gear or grooved wheel 35 which is connected by a gear train, chain, or cable 36 as the case may be, to a suitable manual control in the cockpit of the airplane. Thus by turning the member 35 the rack 32 and the rod 37 operating in the rotating housing 38 formed in the inner end of the drive shaft 6 is caused to slide to the right or left in Figure 1 depending on the direction of rotation or movement of the member 35. The inner end of the rod is supported in a bearing 39 within

the head 40. Since the outer end of the rod or rack 32 is of polygonal cross section and rests in a seat of similar cross section in the support 31, the rack 32 and its integral rod portion 37 do not rotate but are limited to a sliding movement only from right to left and vice versa in Figure 1.

The head 40 rotating with the housing 38 is provided with an extension 41 to which a plate 42 is secured. Racks 43 and 44 are secured at one end to the plate 42 and are slideable in the recesses 45 formed in the drive shaft and have their teeth disposed in diametrically opposed directions to mesh with the teeth of the respective pinions 46 and 47. A pin 48 keys the drive shaft 6 with the rotor 5 so that the two rotate together as a unit.

Referring now more particularly to Figure 2, it will be seen that the pinions 46 and 47 are keyed respectively to the rods 49 and 50 which are rotatably supported in bearings 51 carried by the rotor 5.

The rods are screw-threaded inwardly of their outer ends as at 52 and extend substantially parallel to each other. It will be noted that the right hand sections of the rods 49 and 50 in Figure 2 are separated metallically by the insulated sections 53 and 54 respectively. This is essential since the right hand ends of the threaded rods carry the insulated yoke or equalizing member 55. The insulated yoke 55 comprises a member substantially U-shaped in side elevation as illustrated in the drawing and is internally threaded at 56 and 57 to receive the threaded ends of the insulated rod sections 49 and 50. Intermediate these threaded openings there is provided a guide member 58 operating in the yoke support 26 insulated from the rotor at 27. The outer extremities of the yoke are turned inwardly and engage the outermost follower discs 29 in the insulated tubes 30.

At the opposite ends of the tubes 10 there is provided a similar structure comprising a yoke 60 having openings reversely threaded to receive the reversely threaded left hand ends of the rods 49 and 50. It is to be noted that the opposite ends of each rod are reversely threaded. In this manner rotation of the rods in one direction will cause the yokes 55 and 60 to move toward each other and opposite rotation will impart a separating movement to the yokes.

It is also to be noted that the yoke 60 need not be insulated from the rotor since the flow of current through the insulated carbon piles 11 may be grounded to the rotor and case after it enters the yoke 60. A return current binding post 61 is carried by the casing member 2.

In Figure 5 I have illustrated by means of a wiring diagram how the governor may be electrically connected in a control circuit such as is disclosed in my copending joint application above identified.

The operation of the present invention as illustrated in the embodiment shown and described is as follows:

The shaft 6 has driving connection through suitable gears or other means or is connected directly with and driven by the engine shaft of an airplane motor. The speed of rotation of the shaft 6 is then in definite relationship with that of the engine shaft. Rotation of the shaft 6 and the rotor 5 will subject the discs of the carbon piles 11 to the action of centrifugal forces, these forces increasing in proportion to the increase in the speed of rotation of the shaft 6 and tending

to separate the discs against the compression of the springs 30, thus increasing the electrical resistance through the carbon piles.

It is the function of the equalizing yokes 55 and 60 to impose a predetermined force of compression on the carbon piles through the springs 30 and as has been described this is accomplished by sliding the rack 32 in the desired direction by turning the gear or wheel 35.

As the force of compression exerted on the discs of the carbon piles is increased the current conductivity of the piles is increased due to better electrical contact between the discs in each pile. Thus it will be seen that the piles may be put under an initial predetermined compression to determine the current value which shall be allowed to pass through the piles.

This value may be defined as that required to operate associated blade pitch controlling mechanism including electrical relays, magnetic clutches and suitable gearing such as is disclosed in my said copending application. With such an initial compression applied to the piles, it will be seen that in operation there will be a definite relationship between the R. P. M. of the engine shaft and the degree of centrifugal force operating upon the discs of the carbon piles to overcome this initial force of compression. As the initial force of compression through the springs 30 is overcome by outward movement of the discs 11 the electrical resistance through the piles is increased and the current passing through the piles is decreased.

Such a condition as is explained above will exist, for instance, when the airplane engine speeds up as in diving with the blades set at a high pitch angle. Under such conditions, it is necessary to vary the pitch immediately to maintain the desired R. P. M. of the engine shaft. The governor is set by the pilot to a proper designation whereby a predetermined R. P. M. of the shaft can be maintained. Any tendency of the engine shaft to exceed the desired R. P. M. value will of course result in an increase in the R. P. M. of the rotor 5 increasing the centrifugal forces on the discs of the two carbon piles, sufficiently to overcome the forces of compression applied through the springs 30, at the same time slightly moving the discs outwardly from each other and thereby increasing the resistance through the piles. A current drop results which is sufficient to actuate a high pitch relay 10 closing a circuit to operate a magnetic clutch to further bring into operation associated means to increase the pitch of the blades of the propeller.

Such an increase in blade pitch will of course increase the load on the engine shaft and cause it to slow down to the preselected R. P. M., whereupon the relay 10 is de-energized.

If the airplane engine slows down as, for instance, in steep climbs, the action of the governor will be such that due to the decreased R. P. M. the centrifugal forces exerted on the discs of the piles will be overcome by the forces of compression exerted through the yokes 55 and 60 and the springs 30. The electrical resistance through the piles is thus decreased increasing the current value passing therethrough to a point sufficient to operate the low pitch relay 71, Figure 5. Thus a low pitch magnetic clutch is energized bringing into operation associated mechanism for decreasing the pitch of the propeller blades. Under these conditions the R. P. M. of the engine shaft builds up until the

current value passing through the carbon piles is such that the low pitch relay 71 is de-energized.

From the above it will be seen that I have provided a simple yet extremely sensitive means for efficiency and automatically controlling and governing the rate of rotation of an airplane engine shaft under varying flying conditions, so that a substantially uniform R. P. M. of the shaft can be maintained.

Furthermore, by means of my invention, I have provided a governor which eliminates lag or break in response to condition requiring a pitch change. Another advantage resides in the fact that the present invention provides means of the above named character by which pitch changes can be made gradually and due to the inherent sensitivity of the device a relatively small change in blade pitch will be required to maintain a selected R. P. M. of the engine shaft.

Various changes may be made in the details of construction and arrangement of parts of my invention without departing from the spirit thereof or the scope of the appended claims.

I claim:

1. The combination with a variable pitch propeller, of an automatic control for maintaining a preselected rate of rotation of an engine shaft driving the propeller, said control comprising a rotor having driving connection with the engine shaft, means carried by said rotor and responsive to the action of centrifugal force for obtaining a variation in the pitch of the propeller blades when the rate of rotation of the shaft varies substantially from a preselected value, said means including an electrical pitch control circuit and carbon pile resistance elements in said circuit and mounted transversely on opposite sides of the axis of rotation of the rotor and means for exerting an initial force of compression upon said carbon piles, said last named means comprising a member slidably axially of the rotor, and compression members movably simultaneously in opposed directions upon movement of the slidable member in one direction to exert forces of compression inwardly of the ends of the respective carbon piles.

2. The combination with a variable pitch propeller, of an automatic control for maintaining a preselected rate of rotation of an engine shaft driving the propeller, said control comprising a rotor having driving connection with the engine shaft, means carried by said rotor and responsive to the action of centrifugal force for obtaining a variation in the pitch of the propeller blades when the rate of rotation of the shaft varies substantially from a preselected value, said means including an electrical pitch control circuit and a carbon pile resistance element in said circuit and mounted transversely of the axis of rotation of the rotor and mechanical means operating axially of said rotor for exerting an initial force of compression on said carbon pile, said last named means comprising a member slidably axially of the rotor, and compression members movable simultaneously in opposed directions upon movement of the slidable member in either direction to exert forces of compression inwardly of the ends of the carbon pile and the respective compression members.

3. The combination with a variable pitch propeller, of an automatic control for maintaining a preselected rate of rotation of an engine shaft driving the propeller, said control comprising a rotor having driving connection with the engine shaft, means carried by said rotor and responsive to the action of centrifugal force for obtaining a variation in the pitch of the propeller blades when the rate of rotation of the shaft varies substantially from a preselected value, said means including an electrical pitch control circuit and a carbon pile resistance element in said circuit and mounted transversely of the axis of rotation of the rotor and mechanical means operating axially of said rotor for exerting an initial force of compression on said carbon pile, said last named means comprising a member slidably axially of the rotor, and compression members movable simultaneously in opposed directions upon movement of the slidable member in either direction to exert forces of compression inwardly of the ends of the carbon pile and the respective compression members.

HARRY P. REIBER.
